UNITED STATES PATENT OFFICE

JAMES QUARTZ, OF NEWTON, MASSACHUSETTS, ASSIGNOR TO F. S. WEBSTER COMPANY,
OF BOSTON, MASSACHUSETTS, A CORPORATION OF MASSACHUSETTS

CARBON BINDER

Application filed March 14, 1928. Serial No. 261,664.

This invention relates to carbon binders.

It has been common to bind together any desired number of sheets of carbon paper between backing and cover sheets so as to maintain the sheets of carbon paper in correct position and to prevent to a large extent their injury by wrinkling, folding, or scraping. In use, carbon-copy sheets of paper are inserted between the carbon sheets and a ribbon-copy sheet of paper is laid upon the cover sheet of the binder and the binder and the sheets are rolled into or placed in the typewriting machine. In the use of such binders, however, it has been found difficult to maintain the alignment of the ribbon and carbon-copy sheets, and to prevent the slipping of the ribbon-copy sheet upon the binder in any way that will not interfere in some manner with the free use of the binder.

It is an object of the present invention to provide a carbon binder of the general type above set forth so arranged that the ribbon-copy sheet of paper on the binder can be maintained in alignment with the carbon-copy sheets in the binder during the use of the binder in the typewriting machine; and also so arranged that no obstacle is presented to the free passage of the entire binder through the machine.

A further object of the invention is the provision of a carbon binder in and on which the carbon and ribbon copy sheets can be laid in advance of use by some inexpensive office employee other than the typist and will remain in assembled condition until used.

A further object is generally to improve the construction of carbon binders.

Fig. 1 is a plan view, partially broken away, of one form of carbon binder embodying the invention.

Fig. 2 is a sectional view of the carbon binder taken along line 2—2 of Fig. 1.

Fig. 3 is a plan view similar to Fig. 1 but illustrating a modified form of binder.

Fig. 4 is a perspective sectional view taken along line 4—4 of Fig. 3.

The binder embodying the present invention comprises any number of carbon sheets 10 which are bound together by a backing sheet 12 which is bent over a margin of the

carbon sheets and forms a cover sheet 14 and entirely covers the carbon sheet both at front and back. The carbon sheets and the backing sheet are sewed together at the folded margin of the backing sheet by a line of stitching 16. The backing and cover sheets 12 and 14 are herein integral but they may be otherwise, in a manner not needing illustration.

In use a plurality of carbon-copy sheets 18 are inserted between the carbon sheets 10 with the similar edges of the carbon-copy sheets bearing against the stitched end of the binder, which thus aligns the carbon-copy sheets in the binder. The backing and cover sheets are provided with aligned notches 20 at their free marginal edges opposed to the stitched end of the binder into which notches the carbon-copy sheets extend so that they can be grasped to remove them, as a group, from the binder. A ribbon-copy paper sheet 22 is placed upon the cover sheet 14, on the outside of the binder and is adapted to receive the direct imprint of the type through the ribbon.

In accordance with this invention, the carbon binder is so arranged that the ribbon copy sheet 22 is held in alignment with the carbon copy sheets and is prevented from slipping out of place during the use of the binder and in a manner that does not interfere with the free use of the binder, and especially in such a manner that the binder is free from any projecting parts that may catch upon the typewriter and prevent or obstruct the free passage of the entire binder between the platen and its cooperating rolls. To this end, the carbon binder is provided with one or more openings or slits in its cover sheet 14 which admit a portion of the ribbon-copy sheet 22 to be inserted therethrough, to lie under the cover sheet, thus to be aligned with carbon copy sheets and to be held in aligned relation therewith both before and during the use of the binder and the assembled papers.

In the construction illustrated in Figs. 1 and 2, the cover sheet 14 is provided with four diagonal slits 24 in its four corners, with the two diagonal slits at the stitched margin of the binder preferably extended close to the line of stitching. The four cor-

ners 22^a of the ribbon copy sheet are inserted through said slits and lie under the cover sheet at the corners thereof and the sheet thus is held in alignment with the carbon-copy sheets during the use of the binder.

5 The paper sheets can be placed in and on the binder by an office boy or other low-salaried employee and will be retained in position prior to use by the typist, thus saving the time of the typist.

10 In the modification shown in Figs. 3 and 4, the cover sheet 14^a of the binder is provided with a slit 24^a which lies parallel with, and adjacent to, the stitched margin of the

15 binder and is of a width at least equal to the width of the ribbon-copy sheet and less than the width of the cover sheet and lies entirely within the cover sheet. One entire margin of the ribbon copy sheet 22^b is adapted to be inserted through the slit and lies under the cover sheet and bears against the stitched margin of the binder, thus to be held in alignment with the carbon copy sheets.

20 With the arrangement shown, the binder presents no obstacle to the free passage of the entire binder about the platen of a typewriter.

25 I have herein shown the invention applied to one form only of carbon binder but many especially arranged packs may be made which involve my invention.

30 The particular binder herein shown is claimed in my copending application Serial No. 187,652, filed April 29, 1927, and the present invention is intended as an improvement on the binder of said application.

I claim:

1. A carbon binder having backing and cover sheets and interposed carbon sheets, all 40 united at one margin, said carbon sheets adapted to receive carbon-copy sheets between them and said cover sheet adapted to receive a ribbon-copy sheet upon it and having an opening therethrough into which a 45 portion of the ribbon copy sheet can enter to lie beneath the cover sheet.

2. A carbon binder having backing and cover sheets and interposed carbon sheets, all 50 united at one margin, said cover sheet adapted to receive upon it a ribbon-copy sheet and having a slit therein through which a portion of the ribbon-copy sheet can pass to lie beneath the cover sheet whereby 55 to be retained against displacement on the cover sheet.

3. A carbon binder comprising backing and cover sheets, and interposed carbon sheets, a line of stitching passed through all of said sheets at one margin thereof, said cover sheet 60 having a slit therein adjacent to said line of stitching through which a marginal portion of a ribbon-copy sheet which is on the cover sheet can pass whereby to hold said sheet against displacement on the cover sheet.

65 4. A carbon binder comprising a backing

sheet, interposed carbon sheets, a line of stitching passed through all of said sheets at one margin thereof, said cover sheet having a slit therein which is adjacent to, and parallel with, the line of stitching and is located entirely within the boundary of the cover sheet and has a width at least equal to the width of a ribbon-copy sheet and is arranged to permit a margin of the ribbon copy sheet to pass therethrough and occupy a position beneath the cover sheet and against the stitched end of the binder.

70 In testimony whereof, I have signed my name to this specification.

JAMES QUARTZ.
